(57) **CLAIM**

The ornamental design for a knife blade hand grip, as shown and described.

DESCRIPTION

FIG. 1 is an isometric view of a knife blade hand grip showing my new design;

FIG. 2 is a front elevational view thereof;

FIG. 3 is a rear elevational view thereof;

FIG. 4 is a top planar view thereof;

FIG. 5 is a bottom planar view thereof;

FIG. 6 is a right side elevational view thereof; and,

FIG. 7 is a left elevational view thereof showing my design. The broken line showings of the knife blade are provided for purposes of environment and form no part of the claimed design.
